UNITED STATES PATENT OFFICE.

ADDISON LEWIS, OF MINNEAPOLIS, MINNESOTA.

SUSPENSORY.

Application filed January 10, 1927. Serial No. 160,105.

- This invention relates to new and useful improvements in suspensories, and an object of the invention is to provide a suspensory including a pouch having a sanitary apron secured thereto, the apron and pouch having means for detachably securing them to a waistband whereby they may be readily removed and destroyed, when necessary, and a new pouch and apron substituted therefor.
- 5 A further object of the invention is to provide a suspensory comprising a pouch having an apron secured thereto and means for detachably securing them to a waistband and, further, having leg straps connecting the rear portion of the pouch with the sides of the apron and cooperating with the waistband to retain the pouch and apron in proper position upon the body.
- 10 A further object of the invention is to provide a suspensory comprising a pouch having an apron secured thereto adapted to be detachably secured to a waistband, and having means for detachably securing the apron and pouch to the waistband, consisting
- 15 of a one-piece sheet-like semi-elastic member having oppositely extending tongues engageable with slots in the apron and waistband to detachably secure the apron and pouch to the waistband, said member further having an elongated guide aperture in the upper portion thereof provided with an opening at one side through which the end portions of the waistband may be inserted thereinto.
- 20 A further object of this invention is to provide a suspensory having a one-piece member for detachably connecting the pouch and apron to the waistband.
- 25 Other objects of the invention reside in the construction of the one-piece member for detachably connecting the apron and pouch to the waistband; the structure wherein pouch and apron are secured together and tapes provided to connect the free ends for holding them in position upon the body; the one-piece connecting member which, in addition to providing means for detachably securing the apron and pouch to the waistband, also provides means for
- 30 adjusting the waistband to fit the body; by the elimination of buttons, snaps or buckles, and, in the general construction of the suspensory, as a whole.
- 35 The particular object of the invention therefore is to provide an improved suspensory of the class described.
- 40 Other objects of the invention will appear from the following description and accompanying drawings and will be pointed out in the annexed claims.
- 45 In the accompanying drawings there has been disclosed a structure designed to carry out the various objects of the invention, but it is to be understood that the invention is not confined to the exact features shown, as various changes may be made within the scope of the claims which follow.
- 50 In the drawings forming part of this specification:
- 55 Figure 1 is a front view of the improved suspensory;
- 60 Figure 2 is a rear view of Figure 1;
- 65 Figure 3 is a view showing the apron and pouch removed from the waistband;
- 70 Figure 4 is a prospective view of the one-piece member for detachably connecting the apron and pouch to the waistband; and
- 75 Figure 5 is a detail view showing the manner of connecting the apron to the waistband.
- 80 The novel suspensory featured in this invention comprises a pouch 6 having an apron 7 secured thereto at its upper portion by such means as the stitching, indicated at 8 on the drawing. Slots 9, similar in appearance to buttonholes, are provided in the reinforced upper portion 10 of the pouch and apron to provide means for detachably securing it to the waistband, as will subsequently be described.
- 85 Leg straps 11 are provided, each having one end secured to the rear portion of the pouch as at 12, and having their other ends secured to the opposite edges of the apron 7 intermediately thereof as shown in Figures 1 and 2. These straps are adapted to encircle the legs of the user to retain the pouch and apron in proper position upon the body. The pouch 6 is preferably open at its rear portion, as shown in Figure 2, and has an opening 13 in the forward portion thereof, as shown in Figures 1, 2 and 3.
- 90 A waistband 14 is provided to support the suspensory upon the body of the user. The end portions 15 of the waistband are reinforced as shown in Figures 1 and 2 and have a plurality of slots 16 provided therein as shown.
- 95 An important feature of the invention resides in the means provided for detachably securing the apron and pouch to the waistband. Such means consists of a one-

piece connecting member 17 constructed of a suitable sheet material such, for instance, as celluloid, which will not tarnish or dis-color, when in constant contact with the body. This member is provided with oppositely extending tongues 18 integrally formed therewith and adapted to be received in the slots 9, provided in the upper reinforced portion of the apron and pouch, as shown in Figures 1, 2 and 5. An elongated aperture 19 is provided in the upper portion of the member 17, and this aperture has an opening 20 in one side thereof whereby the reinforced end portions 15 of the waistband may be readily inserted thereinto, as shown in Figure 5. This aperture provides guides for the end portions 15 of the waistband when in position upon the body and as shown in Figures 1 and 2.

20 In securing the suspensor to the body, the tongues 18 in the connecting member 17 will be inserted in the slots 9 in the upper portion of the apron and pouch, as shown at the right-hand side of Figure 5. The reinforced end portions 15 of the waistband 14 are then inserted in the guide aperture 19 and the tongues 18 inserted through the slots 16 as shown at the left-hand side of Figure 5 and in Figure 1. By the use of the member 17 the pouch and apron may be quickly secured to the waistband and by the provision of the slots 16 the waistband may be adjusted to suit the girth or waist-line of the wearer.

35 The one-piece connecting member 17 is comparatively large so as to properly retain the pouch and apron in position upon the body when attached to the waistband 14. Also as a result of the member 17 being constructed of semi-flexible sheet material and as a result of the novel means provided thereon for detachably connecting the pouch and apron to the waistband, the portion of the suspensor lying against the abdomen 40 of the wearer will be comparatively smooth so that it will not interfere with clothing, etc., and it will also be very comfortable to the wearer. Also by the employment of this one-piece member for connecting the pouch and apron to the waistband, the use of buttons, snaps and buckles is dispensed with, which is of considerable advantage in articles of this kind. When desired, the pouch and apron may quickly be removed 45 from the waistband when desired and a new pouch and apron substituted therefor.

I claim as my invention:

1. A suspensor, comprising in combination, an apron having slots therein, a pouch secured to said apron, a waistband for supporting the apron and pouch upon the body, and a one-piece sheet like member for detachably connecting the apron and pouch with the waistband, said member comprising 60 oppositely extending tongues engageable with the slots in said apron to detachably secure the latter thereto.

2. A suspensor, comprising in combination, an apron having slots therein, a pouch secured to said apron, a waistband for supporting the pouch and apron upon the body, slots in the end portions of said waistband, a one-piece member of semi-elastic sheet material for detachably connecting the apron and pouch with the waistband, said member 70 having oppositely extending tongues engageable with the slots in the apron and the slots in the waistband for detachably and adjustably securing the apron and pouch to the waistband.

3. A suspensor, comprising in combination, an apron having slots therein, a pouch secured to said apron, a waistband for supporting the pouch and apron upon the body, slots in the end portions of said waistband, 75 a one-piece member for detachably connecting the apron and pouch with the waistband, said member having oppositely extending tongues engageable with the slots in the apron and the slots in the waistband for detachably and adjustably securing the apron and pouch to the waistband, and said member also having an elongated opening 80 in its upper portion adapted to receive the ends of the waist-band to provide guides 95 therefor.

4. A suspensor including an apron having a pouch secured thereto, a waistband for the apron and pouch, leg straps each having one end secured to the rear portion of the 100 pouch and having their other ends secured to the opposite edges of the apron and co-operating with the waistband to retain the apron and pouch in position upon the body.

5. A suspensor including a pouch, having 105 an opening in one side thereof, a waistband for the pouch, a one-piece member for detachably securing the pouch to the waistband, said member comprising oppositely extending tongues engageable with means 110 in the upper portion of said pouch and in said waistband for detachably securing the pouch to the waistband.

6. A suspensor, comprising in combination, an apron having slots therein, a pouch 115 secured to said apron, leg straps connected with the rear portion of the pouch and with the edges of the apron, a waistband having slots in the end portions thereof, a one-piece member for detachably securing the apron 120 and pouch to the waistband, said member comprising means engageable with the slots in the apron and waitsband for detachably securing the apron and pouch to the waistband, said member further having an elongated aperture in the upper portion thereof adapted to receive the end portions of the waistband to provide guides therefor, said aperture having an opening at one side 125 thereof whereby the end portions of the 130

waistband may be inserted into said aperture and removed therefrom while connected with the apron.

7. The combination with a suspensory including an apron having a pouch secured thereto and a waistband for supporting the apron and pouch upon the body, of a one-piece sheet-like member for detachably securing the apron and pouch to the waistband, said member comprising oppositely

extending tongues adapted to detachably secure the apron and pouch to the waistband and, further, having an elongated curved guide aperture in the upper portion thereof open at one side for the lateral insertion of the end portions of the waistband thereinto. 15

In witness whereof, I have hereunto set my hand this 30th day of December, 1926.

ADDISON LEWIS.
